UNITED STATES PATENT OFFICE

ARTHUR W. LYONS, OF BALTIMORE, MARYLAND

OIL STOVE

Application filed April 24, 1928. Serial No. 272,391.

The present invention relates to an oil stove and has for its prime object to provide a structure comprising a heating drum disposed above an oil burner and means inside of the drum for distributing or deflecting the heat toward the drum. Another very important object of the invention resides in the provision, in a stove of this nature, of means at the top of the drum, for retaining the heat therein or allowing the same to escape freely therefrom.

A further very important object of the invention resides in the provision of a stove of this nature having a heating drum above an oil burner, with rods extending therethrough and bracing the drum structure, and supporting a deflector in the drum so as to cause the heat to engage with the drum, for properly distributing the heat in a room or the like.

Another very important object of the invention resides in the provision of a flange disposed about the drum for further keeping the heat down and distributing the same in the room.

A still further very important object of the invention resides in the provision of a stove of this nature which is simple in its construction, inexpensive to manufacture, strong and durable, thoroughly efficient and reliable in use, and otherwise well adapted to the purpose for which it is designed.

With the above and numerous other objects in view as will appear as the description proceeds, the invention resides in certain novel features of construction and in the combination and arrangement of parts as will be hereinafter more fully described and claimed.

40 In the drawing:

Figure 1 is a side elevation of a stove embodying the features of my invention.

Figure 2 is a sectional elevation thereof.

45 Figure 3 is a horizontal transverse section therethrough taken substantially on the line 3—3 of Figure 2.

Figure 4 is a detail sectional view of the deflector, and

50 Figure 5 is a plan view of an asbestos washer.

Referring to the drawing in detail, it will be seen that the numeral 5 indicates a supporting structure having legs 6. A cylindrical casing 7 is disposed to rise from the supporting structure 5 and house a conventional oil burner 8 of preferred construction. A top 9 is hingedly mounted, as at 10, on the cylindrical casing 7, and includes an inverted frusto-conical portion 11, which merges into a depending cylindrical portion 12 surrounding the burner 8.

An asbestos washer 14 is disposed on the frusto conical portions 11 and has a sheet metal washer 15 disposed thereover. An annular flange 16 rises from the cover 5, about the frusto conical portion 11. Rods 17 rise from the cover immediately inside of the flange 16. A centrally enlarged drum 18 merges at its lower end into a cylindrical collar 19 telescoped over the cylindrical flange 16, and at its upper end into a cylindrical extension 20. The drum proper is made in two sections, riveted together, as at 18', the upper section at its lower end merging into an outwardly and downwardly inclined annular flange 21 made integral therewith. A hollow inverted pear shaped deflector 22 is provided with a pair of depending spaced parallel sleeves 23, extending from the lower intermediate portion of its side wall. The deflector is closed except for apertures through which rods 17 extend and its top face is of greater diameter than its bottom. The structure of such deflector prevents counter-convection currents internal 85 of the drum. The rods 17 extend through the sleeves 23 and through the top wall of the deflector. The lower ends of these sleeves rest on the washer 15, thus supporting the deflector above the burner, to cause it to spread the heat out to the sides for heating the drum 18 thoroughly. The cylindrical extension 20 is provided with an annular series of openings 25. A cover 26 is secured on top of the cylindrical extension 20, by 95 means of rivets 27 and the upper ends of the rods 17. This cover 26 is perforated as is indicated at 28 and a perforated disc 29 is rotatable under the cover as indicated at 30 and has a handle extension 31 through 100

a slot in the cover so that the disc may be revolved.

This will register or unregister the openings 33 in the disc 29 with the openings 28. 5 Thus the heat may be retained in the drum, or allowed to escape freely therefrom.

It is thought that the construction, operation, utility and advantages of this invention will now be quite apparent to those skilled 10 in this art, without a more detailed description thereof.

The present embodiment of the invention has been disclosed in detail merely by way of example, since in actual practice it attains 15 the features of advantage enumerated as desirable in the statement of the invention and the above description.

It will be apparent that changes in the details of construction and in the combination 20 and arrangement of parts may be resorted to, without departing from the spirit or scope of the invention as hereinafter claimed or sacrificing any of its advantages.

Having thus described my invention, what 25 I claim as new is:

1. A device of the class described comprising a supporting structure, a cylindrical casing rising from the supporting structure, a burner in the casing, a cover for the casing 30 having an opening through which the burner projects, rods rising from the cover, a drum rising from the cover about the rods, a hollow closed deflector having spaced parallel sleeves depending downwardly therefrom and resting on the cover, said rods extending through 35 the sleeves and through a portion of the deflector.

2. A device of the class described comprising a supporting structure, a cylindrical casing rising from the supporting structure, a burner in the casing, a cover for the casing 40 having an opening through which the burner projects, rods rising from the cover, a drum rising from the cover about the rods, a hollow closed deflector having spaced parallel sleeves depending downwardly therefrom and resting on the cover, said rods extending through the sleeves and through a portion of the deflector, 45 said drum being bulged at its intermediate portion and terminating at its lower end in a cylindrical collar, a cylindrical flange rising from the cover over which said collar telescopes, the upper end of the drum having a cylindrical apertured extension, a cover over 50 the extension and provided with apertures, an apertured disc rotatable under the second cover for registering and unregistering the apertures with the apertures of the second cover, said rods being engaged with the second cover.

3. A device of the class described comprising a supporting structure, a cylindrical casing rising from the supporting structure, a burner in the casing, a cover for the casing 55 having an opening through which the burner projects, rods rising from the cover, a drum rising from the cover about the rods, a hollow closed deflector having spaced parallel sleeves depending downwardly therefrom and resting on the cover, said rods extending through 60 the sleeves and through a portion of the deflector, said drum being formed in sections and an outwardly and downwardly inclining annular flange merging from the lower edge of the upper section.

deflector, said drum being bulged at its intermediate portion and terminating at its lower end in a cylindrical collar, a cylindrical flange rising from the cover over which said collar telescopes, the upper end of the drum having a cylindrical apertured extension, a cover over the extension and provided with apertures, an apertured disc rotatable under the second cover for registering and unregistering its apertures with the apertures of the second cover. 70 75

4. A device of the class described comprising a supporting structure, a cylindrical casing rising from the supporting structure, a burner in the casing, a cover for the casing having an opening through which the burner projects, rods rising from the cover, a drum rising from the cover about the rods, a hollow closed deflector having spaced parallel sleeves depending downwardly therefrom and resting on the cover, said rods extending through the sleeves and through a portion of the deflector, said drum being bulged at its intermediate portion and terminating at its lower end in a cylindrical collar, a cylindrical flange rising from the cover over which said collar telescopes, the upper end of the drum having a cylindrical apertured extension, a cover over the extension and provided with apertures, an apertured disc rotatable under the second cover for registering and unregistering the apertures with the apertures of the second cover, said rods being engaged with the second cover. 80 85 90 95

5. A device of the class described comprising a supporting structure, a cylindrical casing rising from the supporting structure, a burner in the casing, a cover for the casing having an opening through which the burner projects, rods rising from the cover, a drum rising from the cover about the rods, a hollow closed deflector having spaced parallel sleeves depending downwardly therefrom and resting on the cover, said rods extending through the sleeves and through a portion of the deflector, said drum being bulged at its intermediate portion and terminating at its lower end in a cylindrical collar, a cylindrical flange rising from the cover over which said collar telescopes, the upper end of the drum having a cylindrical apertured extension, a cover over the extension and provided with apertures, an apertured disc rotatable under the second cover for registering and unregistering the apertures with the apertures of the second cover, said rods being engaged with the second cover. 100 105 110 115 120 125

In testimony whereof I affix my signature.
ARTHUR W. LYONS.
